UNITED STATES PATENT OFFICE.

JOHN J. DALY, OF NEW BRUNSWICK, NEW JERSEY, ASSIGNOR TO EDWARD W. McCARTY, OF NEW YORK, N. Y.

DOOR-CHECK.

1,102,727.

Specification of Letters Patent.

Patented July 7, 1914.

Application filed November 22, 1913. Serial No. 802,346.

To all whom it may concern:

Be it known that I, JOHN J. DALY, a citizen of the United States, residing at New Brunswick, in the county of Middlesex and State of New Jersey, have invented certain new and useful Improvements in Door-Checks, of which the following is a full, clear, and exact description.

This invention relates to door checks and 10 more particularly to the type of check which comprises a cylinder having a piston therein which is inserted in the door frame; a member fastened to the edge of the door which abuts the frame when the door is closed; a 15 single link pivotally connected to the door and member respectively; and a spring in the cylinder acting against the piston and correlative parts to close the door, which movement is retarded by restricting the escape of air trapped in the cylinder to the rear of the piston.

One object of my invention is to provide a door check of this character which will permit the door to be fully opened and will 25 continually exert a tension on the door to close it even when it is in its fully opened position.

Another object of my invention is to provide a check which is automatically adjustable for doors and door frames of different sizes.

With these and other objects in view, my invention consists of forming a projecting lug on the member fastened to the door and connecting this lug to the piston-rod by a link of sufficient length to permit the door to fully open, that is, to a position in which the edge of the door lies in substantially the same plane as the face of the frame; the 35 projecting lug extending beyond the edge of the door a distance sufficient to maintain the link at an obtuse angle to the piston-rod when the door is in its fully open position, so that the tension exerted by the spring on the piston-rod will act on the lug through 40 the connecting link to rotate the door to its closed position, which movement is facilitated by the leverage obtained on the door by using a lug which projects a considerable 45 distance beyond the axis of the hinges thereof.

My invention also contemplates making the connecting link of resilient material so that it will adjust itself to the various sizes

of doors and door frames with which it is used.

In the drawings: Figure 1 is a vertical central section through a form of door check embodying the features of my invention, a portion of the door frame also being shown in section; Fig. 2 is a central horizontal section through one of the cylinders of the check; Fig. 3 is a view similar to Fig. 2 but showing the door in its fully open position.

The device is adapted to be attached to the ordinary form of door frame or jamb 1 and a door 2 which is mounted on the frame by hinges 3. Inserted in a rectangular recess perpendicular to the face of the door frame is a casing 4 whose outer face is substantially flush with the face of the door frame, the casing providing duplicate cylinders 6 separated by an intermediate wall 5. Pistons 7 having piston-rod 8 integral therewith are located in each of the cylinders, the pistons serving as a backing for the cup-shaped packing disks 9 of leather or other flexible material which are held against the pistons by washers and nuts 80 threaded on the reduced ends of the same. These packing disks prevent the escape of air between the peripheral edge of the piston and the walls of the cylinder upon rearward movement of the pistons, and are utilized to retard the rearward movement of the piston as will hereinafter be referred to. Internal collars 10 are located in the cylinders 6 adjacent their front ends and are maintained in position by tapered pins 11 90 fitting in recesses or grooves formed in the peripheral walls of the collar and in the walls of the cylinders, respectively, the pins being tapered to permit of their ready removal. Within the cylinders 6 are coiled 95 springs 12 which bear against the collars 10 and the pistons 7 to urge the latter rearwardly to exert a tension on the door to close the same through the connections which will now be described.

Inset in the edge of the door 2 with its outer face substantially flush therewith, is a plate 14. This plate has lugs or projecting members 15 arranged thereon so that when the door is in its closed position, the lugs or projecting members will enter the open ends of the cylinders 6 as is shown in Figs. 1 and 2. The lugs 15 project a considerable

distance beyond the edge of the door for a purpose which will be fully brought out in the operation of the device. A single link 16 connects each of the piston-rods 7 and the lugs 15, and in my preferred construction, this link comprises a tightly coiled spring of less resiliency than the resiliency of the spring 12, and which will not be placed under tension until the spring 12 has been fully compressed. This spring is fastened to the lugs 15 and the piston-rod 8 by bending the ends of the springs around rollers 17 carried by pins 17 driven through the ends of the rod and lugs, respectively, which are preferably slotted for the reception of the bent ends of the springs.

Where the door check is to be used with doors and door frames of various sizes, a connecting link, which consists of the tightly coiled spring 16, is preferable, for if the length of this spring should not be sufficient to permit the door to fully open, then it is evident that after the spring 12 has been fully compressed and the end of the piston-rod 7 projects beyond the face of the casing, as shown in Fig. 3, the coiled spring 16 will then be stretched sufficiently to permit the movement of the door to its widest possible position, the collar 10 forming a bearing for the rod to prevent it from tilting.

In fastening a door check of this kind to the door, it is preferable to do so when the door is in a partially open position, so that the coiled spring 16 will not be under tension and the check may then be secured to the door in the same way as if a rigid link were used. It may also here be noted that since the spring 16 is not under tension, except when the spring 12 is fully compressed, that during all positions of the door other than the fully open position thereof, the coils of the spring 16 will abut each other and form a substantially rigid link, so that the operation of the device, whether a rigid link or a coiled spring is used as a connecting link, is substantially identical.

To prevent the slamming of the door, the rearward movement of the piston-rod 7 is retarded, which is accomplished by providing conduits 18 and 18' which lead from the rear ends of the cylinders and are connected to a common conduit 19 extending through the intermediate wall 5 to the front 55 of the casing. The passage of air through these conduits is controlled by a screw-plug 20 threaded into an enlarged end of the conduit 19, the coned end of the plug being adjustable with respect to a seat 21. The air which is trapped in the cylinders escapes around this seat and through a longitudinal slot 22 cut in the periphery of the plug.

The operation of the device is as follows:—Assuming that the door is in its closed position, as shown in Figs. 1 and 2,

and it is then fully opened to the position shown in Fig. 3. This movement of the door will draw the piston 7 and piston-rod 8 forwardly in the cylinder against the action of the spring 12 until this spring is fully compressed and the end of the piston-rod projects slightly beyond the outer face of the casing. During this movement of the piston-rod, the spring or resilient link 16 will move forwardly and simultaneously swing outwardly to follow the movement of the lug 15. This angular movement of the link is at first slight due to the length of the lug 15, so that the link will leave the casing without binding against the collar 10 or the outer edge of the casing. As the door approaches its fully open position, this angular movement is increased, but the link will have by this time advanced sufficiently in the cylinder to permit the rear end of the link to clear the collar and the edge of the casing and the piston-rod will have reached substantially the position shown in Fig. 3, *i.e.*, with its end projecting beyond the front face of the casing. The parts are now in the position shown in Fig. 3, that is, with the edge of the door lying in the plane of the face of the jamb. Since the lug 15 projects a considerable distance beyond the edge of the door and also beyond the end of the piston-rod 7, the resilient extensible link 16 will form an obtuse angle with this rod, and the tension of the spring 12 acting against this rod will have a component force which will exert a tension on the link and projecting lug to return the door to its closed position. The effect of this force will also be increased since a better leverage is obtained on the door by using a lug which projects a considerable distance beyond the pivotal point of the door. It will therefore be seen that the danger of the door being locked in its open position as would occur if the link 16 was at right angles to or formed an acute angle with the piston-rod, is substantially eliminated. For if the link and piston-rod were at right angles, it is apparent that there would be no component force in the direction of the link so that the door will remain open, and if the link formed an acute angle with the rod, then the component of the force would exert its tension in a direction to lock the door in its open position. After the spring 12 has been completely compressed and the end of the piston-rod projects slightly beyond the outer face of the casing, the resilient link 16 will be placed under tension as the door approaches its fully open position. When the door is released, the tension of the spring 16 will initiate the closing movement of the door and after the spring 16 resumes its normal position, it will act similar to a rigid link as has been previously described, while the spring 13 acts to complete the closing of

the door. It will therefore be seen that the tension of springs 16 and 13 will be successively brought into action to effect the closing movement of the door, which will give 5 a very efficient and practical form of door check.

Having described my invention, I claim:

In a door check, a cylinder adapted to be inserted in the jamb of the door, a piston 10 and a piston-rod connected thereto in said cylinder, a member adapted to be fastened to the edge of the door which abuts the face of the jamb when the door is closed, a resili-ent extensible link pivotally connecting said

rod and said member, and a spring of less 15 resiliency than said link acting against said piston-rod to maintain the door closed, said member projecting beyond the edge of the door sufficiently to maintain said resilient link straight and at an obtuse angle to the 20 piston-rod when the edge of the door lies in the plane of the face of the jamb.

In witness whereof, I subscribe my signature, in the presence of two witnesses.

JOHN J. DALY.
